Filed May 23, 1963, Ser. No. 282,636

4 Claims. (Cl. 139—185)

The instant invention relates to looms of the fly-shuttle type and, more particularly, to the shuttle-engaging binders thereof.

It is a general object of the invention to provide a binder for a shuttle box which will be capable of absorbing and withstanding the increased impact energy resulting from high loom speeds with either wooden or molded shuttles.

A further object of the invention is to provide a binder in which the heat dissipation will be rapid and thereby extend the useful life of the friction material.

A further object is to provide generally good boxing conditions by presenting a yielding wear-resistant surface for meeting and restraining the incoming shuttle.

A still further object of the invention is to reduce shuttle wear through the use of a cooler friction surface in contact with the sidewall of the shuttle.

A further object is to provide a yielding binder friction of unitary construction adapted for easy application or removal to existing loom binders.

These and other objects of the invention will become apparent as further details are disclosed.

In looms where a shuttle is used to transport the filling yarn across the width of the fabric, the shuttle must be abruptly stopped and accurately restrained within the shuttle box in preparation for the return flight through the warp shed. As this operation is repeated a number of times each second, the proper functioning of the binder mechanism is all important to successful weaving.

As the operating speed of automatic looms has been gradually increased and as heavier shuttles carrying greater quantities of filling have been introduced, numerous methods have been devised to deal with the excessive wear encountered in the friction materials of shuttle boxes. These have not been entirely satisfactorily as rapid wear has continued to hold the repair and replacement costs for binder material and shuttles at a high level. Also, in some instances other members of the loom, such as pickers and check straps, have experienced premature failure due to their absorption of the shuttle energy more properly absorbed by the binder friction material.

This invention deals with the loom binder which is the pivotal member of the shuttle box and, in many looms, is adapted to perform two important functions. The first is that of actuating the loom protection mechanism whereby the loom will come to an abrupt stop if the shuttle is not completely in a shuttle box at the time of beat-up. At each pick toward a particular shuttle box, the shuttle is caused to strike the swell of the binder face and thereby pivot the binder outwardly of the box. This in turn will raise the protection device and allow the loom to continue unchecked. The second function is that of frictionally engaging one side wall of the shuttle as it enters the shuttle box and, with spring pressure, of holding the shuttle against the front box plate to aid effectively in checking its flight and in holding it against rebounding.

The heat generated by the shuttle as it strikes the binder at high speeds is sufficient to break down the friction materials presently used in a shorter period than is considered desirable. This has necessitated early replacement and has at times caused damage to the shuttle.

The invention will be described by reference to specific

2

embodiments thereof as illustrated in the accompanying figures of drawing, wherein:

FIG. 1 is a plan view of the left-hand shuttle box of a loom with the invention in place thereon;

FIG. 2 is a plan view of a first modification of the novel binder;

FIG. 3 is a plan view of a second modification;

FIG. 4 is a vertical section on line 4—4 in FIG. 2; and

FIG. 5 is a horizontal section on line 5—5 in FIG. 1.

Now referring to FIG. 1, a shuttle box for a loom is shown to establish the location of the instant invention and comprises a lay end 10 and a picker 11 which is fastened to the upper end of a picker stick 12. The picker stick is arranged to pick the shuttle 13 toward the opposite shuttle box by its intermittent inward motion through a slot (not shown) in the floor of the lay end 10. The picker 11 serves as the endwall of the shuttle box and is that which finally deters the shuttle in its flight through the warp shed.

The forward wall of the shuttle box is the front box plate 14 which is secured to the lay end 10 by bolts 15 and 16. A back box plate 17 which acts to direct the shuttle into the box is shown broken away. Fastened to the lay 10 at a pivotal point 18, a binder becomes the rear confining wall of the shuttle box where the shuttle is held during the beat-up action of the loom. The inward end of the box remains open to receive and discharge the shuttle in a well-known manner.

The body of the binder is a rigid member 19, generally made of wood, which is pivotally supported at the point 18 by the lay end 10. The binder member 19 when placed in the shuttle box presents a forward surface 20 toward the front of the loom. The forward surface 20 faces the shuttle when it is in the shuttle box and in the forward surface 35 is cut a transverse recess 21 which covers the full width of the rigid member 19. The length of the recess 21 may extend from the swell of the binder, or that point first contacted by the shuttle, longitudinally a majority of the binder length. In FIG. 1 it will be seen that the recess 21 exceeds the length of that surface contacted by the shuttle while in the box. The depth of the recess should be about one-quarter of an inch and follow the contour of the binder face 20.

In FIG. 2 a modification is shown in which the transverse recess 21' is shorter than in the preferred embodiment and covers only that area of the binder face which is first contacted by the incoming shuttle. A second modification is seen in FIG. 3 where the transverse recess 21² is tapered from a full depth near the inward end of the binder to the face of the forward surface 20 centrally of the binder. These and other possible modifications differ only in the conformation of the transverse recess so that other parts in FIGS. 1, 2, and 3 which are similar will have like numerals.

The forward surface 20 of the binder is substantially fully covered by a shuttle engaging member, generally designated 22, which is formed for application to the rigid binder member 19 as a unit by having the individual parts molded together. A resilient outer surface 23 of high density felt offers a frictional contact with the incoming shuttle to assist in stopping its flight and in holding it from rebounding. Beneath the outer surface 23, a flexible under surface 24 of plied coated canvas supports the felt surface and also a molded rubber insert comprising a series of pillar-like projections 26. These projections are held spaced apart and act to support the felt surface 23 in a yieldingly flexible manner when inserted into the recess 21. The ends of the projections 26² (FIGS. 2 and 5) may be cemented to the rigid binder 19; however, in many instances this has not been necessary. The projections may assume varied formations

such as round, square, conical, pyramidal, or a combination. In the present embodiment the form is round with an enlarged conical base. The projections are pressed vertically into the recess 21 interconnecting the rigid member 19 with the shuttle engaging member 22. As the shuttle engaging member is extended over the recess 21, it is supported in a continuing line from both ends of the forward surface 20.

The shuttle engaging member 22 is formed as a single unit which may be applied to the binder 19 by adhesives or mechanical means for installation or replacement. The individual parts of the unit are combined by molding with thin sheets of uncured rubber separating each part and an additional sheet of rubber to form the projections 26. The application of heat and pressure to the mold makes a laminated unitary binder covering in which the outer surface 23 is of felt and the lower supporting side is a series of rubber projections 26.

The rubber used in the unit for molding the projections and for combining the canvas layers and the felt layer may be one of a range of rubber-like substances from SBR to neoprene or Hycar.

It will be seen that when it is necessary to replace the binder surface a complete unit is installed in which the height of the projections and felt covering will be consistent with the one being removed. This eliminates the necessity for binder adjustments usually required when such replacements were made.

The flexible under surface 24 formed of two or more layers of canvas as, for example, woven cotton, molded between thin layers of rubber adds greatly to the stability of the felt outer surface 23, which may be of wool, particularly where it is extended over the recess 21.

In the second modification (FIG. 3) the projections 26' are molded to conform to the declining graduated height of the tapered recess 21². The projections in each of the embodiments form a cushioning member to absorb the shock of the shuttle striking the binder while entering the shuttle box.

The binder 19 is pivoted inwardly of the shuttle box when the shuttle is absent by a leaf spring 27 which is fastened to the lay end 10. As the shuttle strikes the surface 23 the binder 19 is pivoted outwardly causing a bumper member 28, which is fastened to the back sidewall of the binder, to rock the loom protection finger 29 in a manner well known in the weaving art.

During high speed weaving the ordinary binder will build up and hold a high temperature. This causes rapid deterioration of the binder leather or other material being used and represents a large portion of the repair parts cost. With the instant invention the spaced apart supporting members allow rapid heat dissipation by a free circulation of air between the shuttle engaging member and the rigid binder. This has been found to be a practical advantage with binder leathers of the usual type and is especially valuable when combined with the felt material or other synthetic textile material to frictionally engage the shuttle.

While one embodiment and two modifications have been disclosed, it is to be understood that the inventive concept may be carried out in a number of ways. The invention is, therefore, not to be limited to the precise details described, but is intended to embrace all variations and modifications thereof falling within the spirit of the invention and the scope of the claims.

We claim:

1. A binder for a loom comprising a pivotally supported rigid member, a transverse recess intermediate

the ends of said rigid member, a resilient shuttle engaging member being fastened to said rigid member extending over the said recess, and a series of pillar-like projections adapted for supporting said shuttle engaging member above said recess, said pillar-like projections extending substantially fully between said rigid member and said shuttle engaging member.

2. A binder for a loom comprising a pivotally supported rigid member, a transverse recess in the forward surface and intermediate the ends of said rigid member, a resilient shuttle engaging member being fastened to the forward surface of said rigid member completely covering said recess, said shuttle engaging member including a flexible under surface with a resilient outer surface for frictionally engaging a loom shuttle, and a series of pillar-like projections resting within said recess being adapted for supporting said shuttle engaging member above said recess, said pillar-like projections extending substantially fully between said rigid member and said shuttle engaging member, said projections being formed integrally with said flexible under surface and said outer surface.

3. A binder for a loom comprising a pivotally supported rigid member, a transverse recess in the forward surface and intermediate the ends of said rigid member, a resilient molded shuttle engaging member being fastened to the forward surface of said rigid member completely covering said recess, said shuttle engaging member including a resilient outer surface for frictionally engaging a loom shuttle, a flexible under surface having a series of pillar-like projections extending substantially fully between said rigid member and said shuttle engaging member formed integrally thereon in closely spaced proximity, said projections being held vertically to the said recess for positioning said shuttle engaging member on a continuing line from both ends of said forward surface of said rigid member, said projections being yieldably flexible under continued impact.

4. A binder for a loom comprising rigid member, a transverse recess in the forward surface and intermediate the ends of said rigid member, a resilient molded unitary shuttle engaging member being fastened to the forward surface of said rigid member covering said recess, said shuttle engaging member including an outer surface of a high density felt material for frictionally engaging a loom shuttle, a flexible reinforcing under surface having a series of pillar-like projections formed integrally thereon in closely spaced proximity, said pillar-like projections extending substantially fully between said rigid member and said shuttle engaging member, said projections being held vertically to the said recess for positioning said shuttle engaging member on a continuing line from both ends of said forward surface, said projections being yieldingly flexible under continued impact.
